UNITED STATES PATENT OFFICE

92,275

DESIGN FOR A TEXTILE FABRIC

Walter D. Teague, New York, N. Y., assignor to
Marshall Field & Company, Chicago, Ill., a cor-
poration of Illinois

Application March 12, 1934, Serial No. 51,013

Term of patent 3½ years

To all whom it may concern:

Be it known that I, WALTER D. TEAGUE, a citizen of the United States, residing at New York, in the county of New York and State of New York, have invented a new, original, and ornamental Design for a Textile Fabric, of which the following is a specification, reference being had to the accompanying drawing, forming a part thereof:

Figure 1 of the drawing is a face view of a piece of fabric embodying a complete unit of the design;

Figure 2 is a detailed enlarged view of a portion of the design shown in Figure 1, on a scale approximately twice the size of Figure 1.

The unit as illustrated in Figure 1 is carried forward over the surface of the fabric in the relation shown, the lining representing contrasting shades and colors.

I claim:

The ornamental design for a textile fabric as shown and described.

WALTER D. TEAGUE.
